STOVE

Benjamin F. Berkheimer, Greenville, Ohio

Application March 17, 1939, Serial No. 262,498

7 Claims. (Cl. 126—4)

This invention relates to stoves and more particularly to the arrangement of a water front or a water-heating chamber that is incorporated into the fire-box or fire bowl of a combined kitchen cook stove and heating stove. This invention relates to stoves similar to the stoves shown and described in my copending applications Serial No. 210,754 filed May 28, 1938, for Heat transfer device now Patent No. 2,171,642, issued Sept. 5, 1939, and Serial No. 249,974 filed Jan. 9, 1939, for Heat transfer device now Patent No. 2,180,788 issued Nov. 21, 1939. In the disclosures in the above identified applications no hot water chamber or water front was provided in association with the fire-box, although reference was made to such a structure. In the embodiment disclosed herein, a fire-box lining is made from two halves, one of which is provided with a water chamber for heating water, which water chamber projects through an opening in the fire-box frame or partition of the stove.

An object of this invention is to provide a combined kitchen cook stove and heating stove, wherein the fire-box lining has incorporated therein a water front or a water chamber for heating water, which water chamber occupies space which has not been taken from the fire-box.

Another object of this invention is to provide a fire-box lining for a combined kitchen cook stove and heating stove wherein the fire-box lining is made from two halves.

Another object of this invention is to provide a combined fire-box lining and water-heating chamber that is easily produced, simple in construction, but at the same time efficient and economical.

Another object of this invention is to provide an outwardly bulging water front which projects into unoccupied space.

Other objects and advantages reside in the construction of parts, the combination thereof and the mode of operation, as will become more apparent from the following description.

In the drawing, Figure 1 discloses a fragmentary side view of the stove with parts broken away, so as to show a portion of the stove in section.

Figure 2 is a fragmentary cross sectional view taken substantially on the line 2—2 of Figure 1.

Figure 3 is a fragmentary cross sectional view taken substantially on the line 3—3 of Figures 1 and 2.

Figure 4 is a perspective view of the fire-box linings, one of which incorporates a water cham-

ber, as this fire-box appears when removed from the stove.

For some purposes it is very desirable to have a combined cook stove and heating stove. This type of stove has been found advantageous in camps, in cabins, in household use in the milder climates and as an auxiliary stove in the more severe climates, augmenting the use of an electric or gas range. Such a stove is found to have considerable heating capacity for heating a room in cool weather.

Due to the varied uses to which this stove may be put, it is very desirable to have a neat appearing stove, that may be cheaply constructed; but at the same time harmonizing with the more expensive and luxurious stoves and surrounding equipment. That being the case, it has been found very desirable to enclose the stove by enamelled panels, so as to present a neat appearance. This has been accomplished by mounting the stove proper, that is, the fire-box of the stove, in the center of the structure and arranging the side panels in spaced relation from the outside of the fire-box, so as to provide air passages between the panels and the fire-box, permitting the circulating air to be heated. In my Patent No. 2,180,788, the inner frame structure is provided with openings exposing the sides of the fire-box to the air circulating through the air passages.

In the present embodiment a water chamber or a water front has been built into one of the halves of a fire-box which is made from two pieces. The water front constitutes an outwardly directed bulge projecting into the opening exposing the fire-box lining to the air passages, so as to utilize space that is otherwise of no particular utility, other than exposing the fire-box lining to the air passages. By incorporating the water chamber on the side of the fire-box lining, so as to project into this opening, the efficiency of the stove is actually increased in the event water is not tapped from the water chamber, in that the metal forming the walls of the water chamber are good conductors of heat, thereby conducting the heat out to the circulating air, as will appear more fully later.

Referring to the drawing, the front end frame member 10 of the stove and the rear end frame member 12 are mounted upon a base not shown, which base is provided with longitudinal slots providing air passages. These end frame members 10 and 12 support a top 20 provided with a flue opening 26 and a pair of overhanging ledges 22 having a series of aligned apertures 24. This top frame member may be provided with a suit-

able lid supporting member 28 supporting a lid 30 terminating in a drop edge fuel feed door 32 having a downwardly projecting lip or flange 34. The sides of the stove are enclosed by a pair 5 of panels 36, one on either side, secured in position as more fully described in my copending application Serial No. 210,754 supra. The panels 36 are provided with a plurality of longitudinal openings 38 along the top thereof, so that air 10 entering through the slots in the base may circulate upwardly and escape through the openings 24 and 38.

The base, which has not been shown, supports a pair of partitions 42, one on either side, which 15 partitions are arranged in spaced relation from the panels 36. These partitions 42 cooperate to form the sides of an ash pit compartment. Each partition 42 is provided with a suitable damper 59, controlled from the front of the stove, as more 20 fully described in my applications supra. The ash pan, which has not been shown, may be removed through a door 56 in the front of the stove.

Suitable grates 60 are supported above the ash 25 pit. Above the partitions 42 are mounted fire pit frame members 62, each provided with inwardly directed flanges 64 on the sides of the opening. An inwardly directed rib portion 66 extends across the top of the opening and continuously across 30 the entire length of the fire pit frame member 62. The upper edge of each member 62 is seated in a suitable channel or otherwise secured to the top member 20. Each of the fire pit frame members 62 is also provided with a sill portion 70, 35 having a downwardly projecting flange 72 merging into an inwardly directed flange 76 that supports the fire-box lining members 80 and 82. The fire-box lining member 80 has an outwardly directed peripheral flange portion 80a. Likewise, 40 the fire-box lining member 82 has an outwardly directed peripheral flange portion 82a. These flange portions 80a and 82a rest upon the rib or flange portion 66 integral with the fire pit frame members 62. In addition thereto, these outwardly 45 directed flange portions rest upon a rib 84 integral with and extending across the front frame member 10 and the rib or flange 86 integral with and extending across the rear end frame member 12.

50 The fire-box lining members 80 and 82 may be held in position by suitable bolts not shown. The fire-box lining member 80 lines one-half of the fire pit and the fire-box lining member 82 lines the other half. These members are joined 55 along the front and along the rear of the fire pit, that is, along the narrow ends of the fire pit. Member 82 is preferably provided with overlapping flanges 82b, so as to provide a more perfect union. The entire periphery extending along 60 the flanges 64, the sill 70 and the rib 66 is sealed with a suitable cement, so as to provide an airtight juncture between frame members 62 and the fire-box lining member 80 or 82 as the case may be.

65 The fire-box lining member 82 is provided with a water chamber 90 that is formed by a bulging portion 92 that projects outwardly through the opening in the fire-box frame member 62, as clearly seen by referring to Figure 2. 70 An intake pipe 93 and an outlet pipe 94 are used for supplying water to the chamber 90 and withdrawing water from this chamber. A horizontal baffle 96 projects into this chamber so as to divide it into two compartments, causing the water 75 passing through the chamber to circulate

throughout the entire length of the water chamber, or substantially so.

When water is not tapped, the water within the chamber becomes hot and conducts heat. The conductivity of the water, together with the conductivity of the metal, aids in transferring heat very rapidly from the inner surface of the lining 5 82 to the extreme outer surface of the bulging portion, so as to expose the air passing through the air passage to this outer surface of the bulging 10 portion. Thus, the use of a water front projecting through the opening in the fire-box frame does not decrease the efficiency of the stove as a heater except when water is withdrawn, when, of course, the cold water will absorb the heat 15 while it is being heated.

The fire-box lining member 82 having the water front bulge therein may be used either on the left hand side or on the right hand side of the stove. The grate shaking handle is usually disposed on the side opposite the water pipes. When the water front is not used, a fire-box lining member similar to member 80 is used instead of member 82. The fire-box lining is then in two pieces, one of which may be removed if it is desirable to insert a fire-box lining with a water front therein. Thus, it is possible to remove one-half of the fire-box lining and substitute therefor another lining having a water front bulge therein. 20 25 30

Although the preferred modification of the device has been described, it will be understood that within the purview of this invention various changes may be made in the form, details, proportion and arrangement of parts which generally stated consist in a device capable of carrying out the objects set forth, in the novel parts, combination of parts and mode of operation, as disclosed and defined in the appended claims. 35

Having thus described my invention, I claim: 40

1. A duo-functional stove for use as a kitchen cook stove and as a heating stove having a pair of end frame members supporting a fire-box in the center and near the top thereof, the combination including a top for the cook stove forming the top of the duo-functional stove and provided with overhanging ledges having marginal apertures, a pair of panel members projecting downwardly in flush relation with the outer edges of the ledges and forming sides of the stove, a pair of fire pit frame members depending from the top arranged in spaced relation from the panels so as to form an air passage between the panels and the fire pit frame members having openings therein, and fire-box lining means having the outside exposed to the air in the air passages through the openings in the fire pit frame members, the fire-box lining means having a water front bulge projecting through one of the openings in the frame members for heating water. 50 55 60

2. A duo-functional stove for use as a kitchen cook stove and as a heating stove, the combination including a frame, a pair of fire bit frame members having heat radiating openings therein, said fire pit frame members being supported upon the first frame member, said fire pit frame members being arranged in parallel relation on opposite sides of the fire pit of the stove, and fire-box lining members mounted between the fire pit frame members and extending over the radiating openings therein, one of said fire-box lining members being provided with a water front bulge extending through one of the heat radiating openings. 65 70 75

3. A duo-functional stove for use as a kitchen 75

- cook stove and as a heating stove, the combination including a frame, a pair of fire pit frame members, each provided with a rectangular opening, said fire pit frame members extending along the sides of the fire pit of the stove, a pair of fire-box lining members cooperating to form a fire-box lining extending around the fire pit, said fire-box lining members extending across the rectangular openings so as to radiate heat through the openings, one of said fire pit lining members having a water front bulge projecting into one of the rectangular openings so as to provide a water heater in one of the fire box lining members.
- 15 4. A duo-functional stove for use as a kitchen cook stove and as a heating stove, the combination including a cook stove top, a pair of fire pit depending frame members projecting downwardly from the cook stove top, said frame members having heat radiating openings therein, fire pit lining members mounted inside of said frame members, said fire pit lining members extending across the openings in said frame members, one of said fire pit lining members having a bulge projecting outwardly through one of said openings, said bulge forming a water heating chamber, and means for interconnecting the water heating chamber to water mains.
- 20 5. A duo-functional stove for use as a kitchen cook stove and as a heating stove having a pair of end frame members supporting a fire-box in the center and near the top thereof, and a pair of side members for enclosing the sides of the stove, the combination including a top for the cook stove, a pair of fire pit frame members depending from the top arranged in spaced relation from some of said members so as to form air passages between said members and the fire

pit frame members having openings therein, and fire-box lining means having the outside exposed to the air in the air passages through the openings in the fire pit frame members, the fire-box lining means having a water front bulge projecting through at least one of the openings in the frame members for heating water.

5 6. A duo-functional stove for use as a kitchen cook stove and as a heating stove having a pair of end frame members supporting a fire-box in the center and near the top thereof, and a pair of side members for enclosing the sides of the stove, the combination including a top for the cook stove, a fire pit frame depending from the top arranged in spaced relation from at least one of said members so as to form an air passage between the sides and the fire pit frame having an opening therein, and fire-box lining means having the outside exposed to the air in the air passage through said opening in the fire pit 10 frame, the fire-box lining means having a water front bulge projecting through said opening in the frame for heating water.

15 7. A duo-functional stove for use as a kitchen cook stove and as a heating stove having a frame structure supporting a fire-box in the center and near the top thereof, the combination including a top for the cook stove supported by said frame structure, a pair of fire pit frame members depending from the top having the outside exposed to the air to be heated, said fire pit frame members having openings therein, and fire-box lining means having the outside exposed to the air through the openings in the fire pit frame members, said fire-box lining means having a 20 water front bulge projecting through one of the openings in the frame members for heating water.

25 BENJAMIN F. BERKHEIMER.
